UNITED STATES PATENT OFFICE.

ALFRED J. URLIN, OF MISSOULA, MONTANA TERRITORY.

KEY-HOLE GUARD.

SPECIFICATION forming part of Letters Patent No. 374,719, dated December 13, 1887.

Application filed October 11, 1887. Serial No. 252,076. (No model.)

To all whom it may concern:

Be it known that I, ALFRED J. URLIN, of Missoula, in the county of Missoula, Montana Territory, have invented a new and useful 5 Improvement in Key-Hole Guards for Door-Locks, of which the following is a specification.

This invention relates to a key-hole guard for covering and obstructing the entrance to the interior mechanism of the lock through 10 the key-hole.

The object of my invention is to provide a guard which will cover the key-hole on both sides of the lock without interfering with the movement of the key when placed within the 15 lock, which will prevent the key from falling out of the lock, and will also prevent persons from the outer side of the door passing another key or picking-tool into the lock; and the improvement consists in certain peculiarities of 20 construction of parts, hereinafter described, and particularly designated in the claim.

In the accompanying drawings, Figure 1 is 25 an elevation of a lock embodying my invention with the front plate removed, with the key-hole and key shown by dotted lines; Fig. 2, a sectional elevation, enlarged, through the hollow slide-block and through the back and front plates of the lock, showing the key in elevation; and Fig. 3, a perspective of the 30 hollow slide-block detached.

My improvements are shown as applied to an ordinary rectangular door-lock, wherein the lock-case A consists of a back plate, A', having a top wall, a, a bottom wall, a', and 35 side walls, a² a³, and of a flat front plate, A², which fits over the back plate with its side walls, and is secured thereon by a screw, a⁴, passing centrally through the front plate into a post, a⁵, projecting from the back plate, and 40 by wood-screws a⁶, passing through both the front and back plates into the door. A latch, B, and latch-stop B', placed in the upper part of the casing, and a bolt, C, having a tumbler, C', and spring C², are all of the ordinary construction used in this class of locks and operate in a well-known manner.

D is a slide-block of novel construction, consisting of a hollow shell with side plates, d d', top cross-plate, d², a bottom cross-plate, d³,

and a thumb-bit, d⁴, projecting from the bottom cross-plate down through a slot, a⁷, in the bottom wall, a', of the lock-case, by which means the slide-block may be easily moved within the lock-case to bring the side plate d of the block across both the inner key-hole, 55 E, and the side plate d' across the outer key-hole, E', of the lock.

The upper corners of the slide-block nearest the key-holes are cut out to partly encircle the pin of the key when placed within the 60 lock and permit the bit of the key to pass through or within the hollow portion of the slide-block and turn freely therein to lift the tumblers and throw the bolt in either direction while the slide-block is in position to 65 guard the key-holes.

The key is by the above-described means prevented from falling out of the lock or from being removed by children or meddlesome persons. The key-hole is so obstructed by the 70 slide-block that persons cannot see through it, and cold air, snow, rain, and sound are prevented thereby from passing from one room to another.

The key is prevented from being turned in 75 the lock from the outside by first moving the slide to open the key-hole, then locking the door and turning the key in the lock until it fills the key-hole, and finally pushing the slide over the key-hole. The door cannot then be 80 unlocked without first pushing the slide back from over the key-hole, which can be done from the inside only.

I claim as my invention and desire to secure by Letters Patent—

The combination, with a lock-case provided with a slot in the bottom wall, of the hollow block D, of a width equal to the space between the front and back plates of the lock-case, and having its upper corners cut away and provided with a thumb-bit, d⁴, projecting through the slot of the case, substantially as herein shown and described.

ALFRED J. URLIN.
